JOHN BEAULIEU AND ERNEST CONNERS, OF EVERETT, WASHINGTON.

SAFETY ATTACHMENT FOR BATHING SUITS.

Application filed December 8, 1924. Serial No. 754,530.

This invention relates to safety attachments for bathing suits and has for its principal object to provide air pockets that can be attached to bathing suits by means of buttons, stitching or other suitable means and which can be inflated in case of emergency to serve as a safety device to prevent drowning.

It is also an object to provide attachments of the above character that may serve as trimmings about the collar, waist or chest of a bathing suit and which may be of a decorative character to enhance the appearance of a suit.

Other objects reside in the details of construction in such strips of valves by means of which the strips may be inflated.

In accomplishing these and other objects of the invention, I have provided the improved details of construction, the preferred forms of which are illustrated in the accompanying drawings, wherein—

Figure 1 is a view of a bathing suit having a collar and breast band of the safety strip embodied by this invention.

Figure 2 is a view illustrating the attachment of the ends of the strip.

Figure 3 is an enlarged cross sectional view of a safety strip.

Referring more in detail to the several views of the drawings—

1 designates what may be a bathing suit of the usual type and to which a collar strip 2 and breast strip 3, constructed in accordance with the present invention, are attached.

In their preferred form of construction the safety strips comprise an elongated pocket made up of a back wall 4 of some durable, but inexpensive fabric, and an outer wall 5 suitable in texture and pattern to match with the material of the bathing suit. Preferably this outer wall would be of a decorative character so that the strips would add to the attractiveness of the suit.

The two strips are stitched together along their longitudinal edges so as to form a pocket in which a tube 6 of rubber or other air tight material is enclosed. The ends of the tube terminate short of the ends of the casing and are sealed so that it may be in-

flated and the ends of the casing are stitched together, as indicated at 7, in Figure 2.

Extended through the outer walls of the casings and tube, preferably at the front 55 of the suit, are valves by means of which the tubes may be inflated. Each valve construction consists of a tube 10 extended through the outer wall of the casing and tube with its outer end clinched over a 60 washer 11 that is placed about the tube and its inner end clinched over a washer 12 from which a valve spring 13 extends; the latter being turned back to underlie the opening of the tube where it is provided with a 65 valve head 14 adapted to be yieldingly held by the opening against the opening to prevent an outflow of air when the tube is inflated.

Such strips may be sewed about their 70 edges to the bathing suit as the collar band is attached in Figure 1, or may be provided at intervals about their edges with button holes 15 adapted to receive buttons 16 attached to the suit as the breast strip is 75 shown attached.

Such strips will be put up in curved form for use as neck pieces and in straight strips for use about the waist and breast and could be made in strips of considerable length to 80 be cut apart to form the individual neck or breast bands. In such strips the ends of the tubes would be indicated by lines of stitching as at 20 in Figure 2, and there would be a space between the ends of adjacent tubes which would leave ends when the strip is cut in two which may be fastened together.

In a cheaper form of construction the back wall of the casing could be of cheese cloth or paper, or the back could be omitted and the air pocket gummed or otherwise fastened to the facing strip.

With a suit equipped with such devices it is possible in case of necessity for the 95 wearer to inflate the tubes by blowing into the valves and in this way provide a buoyant support.

Having thus described our invention, what we claim as new therein and desire to secure 100 by Letters-Patent, is:

The combination with a bathing suit, or

the like, having buttons attached thereto, of an inflatable air pocket in strip form adapted to encircle the suit; said pocket having a casing adapted to be secured together at its ends and having button holes along its edges for receiving said buttons to thereby detachably secure the device to the suit, and a valve tube extended through the

casing into the pocket whereby the latter may be inflated and a back check valve at 10 the inner end of the tube.

Signed at Everett, Snohomish County, Washington, this 18th day of August, 1924.

JOHN BEAULIEU.
ERNEST CONNERS.
